RACK FOR BICYCLES AND THE LIKE

Donald L. Branscom, 1816 E. Helen St., Apt. 209,
Tucson, Ariz. 85719

Filed Mar. 11, 1974, Ser. No. 449,960

Term of patent 14 years

Int. Cl. D12—11

U.S. Cl. D12—158

FIG. 1 is a perspective view of a rack for bicycles and the like showing my new design;

FIG. 2 is a top plan view thereof;

FIG. 3 is a right side elevational view thereof, with the downwardly extending supports being broken away in the middle for convenience of illustration; and

FIG. 4 is a front elevational view thereof, with the lower portion of downwardly extending supports being broken away for convenience of illustration.

I claim:

The ornamental design for a rack for bicycles and the like, as shown and described.
